UNITED STATES PATENT OFFICE.

ARTHUR EDGEcumbe RENDLE, OF PHILADELPHIA, PENNSYLVANIA, ASSIGNOR TO
KEYSTONE TYPE FOUNDRY, OF PHILADELPHIA, PENNSYLVANIA, A CORPORATION
OF PENNSYLVANIA.

SKYLIGHT.

1,272,100.

Specification of Letters Patent.

Patented July 9, 1918.

Application filed April 10, 1917. Serial No. 161,051.

To all whom it may concern:

Be it known that I, ARTHUR E. RENDLE, a subject of the King of Great Britain, residing at Philadelphia, Philadelphia county, 5 and State of Pennsylvania, have invented and discovered certain new and useful Improvements in Skylights, of which the following is a specification.

My said invention consists in certain improvements in the details of construction of 10 skylights for buildings, particularly skylights of the type composed of glass and metal, all as will be hereinafter more fully described and claimed.

Referring to the accompanying drawings, 15 which are made a part hereof, and on which similar reference characters indicate similar parts,

Figure 1 is a view, partly in section and 20 partly in elevation, through a portion of a skylight constructed in accordance with my said invention, and

Fig. 2 a cross section on the dotted line 2—2 in Fig. 1.

In said drawings, the portions marked A 25 represent the steel portions of the frame of the roof construction to which the skylight bars are secured, B longitudinal skylight bars formed of channel-irons, and C the 30 glass sections mounted on the upper edges of said channel-iron supports.

Said glass sections C are formed with longitudinal corrugations in their top surfaces and are mounted on the top edges of 35 the channel-bars B, roller bearings 10, of lead or other suitable material, being interposed between the top edges of the bars and the under surface of the glass sections. These lead bearings are cylindrical in form, 40 as best shown in Fig. 2, having longitudinal openings in their under sides of a width to permit an oscillatory movement on the edges of the channel-irons when necessary, thereby providing for contraction and expansion of 45 the frame-work and the vibration of the building, without danger of breaking the glass. Said glass sections are spaced apart substantially as shown in Fig. 2, and a cap bar 11 is mounted to cover the space between 50 their adjacent edges. Said cap bars 11 are each of the form to provide depending edges, which are adapted to fit into or seat in the longitudinal grooves of the glass and thus form a tight joint. As illustrated in Fig. 2,

I have shown these cap bars as roof-shaped 55 in cross-section. Many modifications of this type of bar, however, will readily suggest themselves to any competent builder or architect, although I deem the form shown as one especially well adapted for the purpose. Said cap bars are held in place by 60 clamping bolts 12, carried on cross-pins 19 and projecting in a vertical direction through apertures in the top of said cap, and have nuts 13 on their upper ends, by 65 which the parts may be tightly clamped together to form a water-tight and a weathertight joint between the glass and the channel-iron supports. The said cross-pins 19 are angular in cross-section, and the eyes of 70 the clamping bolts 12 are of corresponding shape, so that the pins, when put in place for assembling the parts, will stand and be supported in an upright position and thus facilitate the placing of the cap bars 11 in 75 position, as it will only be necessary to slide the cap bars until the perforations therein register with the upper ends of the bolts, when they will fall into place, the bolts and the holes in the cap bars being spaced uniform distances apart. The nuts 13 may then 80 be adjusted. I have shown said cross-pins 19 and the eyes of the clamping bolts as diamond-shaped, but it will be understood 85 that any other angular shape in cross-section will accomplish the same result.

Another feature of my construction, to which I make special claim, is the channel-shaped support 14 for the upper skylight bars, interposed between the adjacent ends 90 of the longitudinal channel-irons B. Said supports serve as supporting brackets and are of channel or angle shape, of the required length, corresponding substantially with the width of the skylight bars. These 95 supports 14 are secured to the roof construction by bolt 15, which bolt also secures the upper end of the lower skylight bar to the roof construction, while the bolt 16 secures the lower part of the upper skylight bar 100 to said support. The ends of the channel-iron supports are covered by metal caps 17 and 18, as shown.

The advantages of the several improvements in the skylight construction, which 105 constitute my said invention, may be briefly recapitulated as follows: The edges of the cap bar, of whatever special form may be

preferred, fitting into the deep grooves in the top surface of the glass, and being clamped therein by the clamping bolts, make a tight joint and render leakage impossible; the roller bearings, between the edges of the channel irons and the under surface of the glass, permit the contraction and expansion of the steel in the framework and also any vibration of the building, without transmitting the strain to the glass plates and causing breakage; the supports 14 enable a skylight to be constructed of a length greater than appropriate for a single pane of glass, by supporting succeeding sections in planes above each other, so that moisture, either on the inside or the outside of the upper panes of glass, will shed onto the pane below, and by supporting the clamping bolts on diamond-shaped cross-pins, as shown, or on pins of other appropriate angular form, they are supported rigidly in a position to receive the cap bars and thus facilitate the assembling of the parts.

25 While I have described my invention as an improvement in skylights and deem it particularly adapted for skylight construction, it will be understood, of course, that the invention may be utilized in window construction of other types, and that, for the purposes of the patent, the term "skylight" embraces any glass and metal structure wherein the invention may be appropriately used.

30 Having thus fully described my said invention, what I claim as new and desire to secure by Letters Patent, is:

35 1. A skylight structure comprising a frame having supporting edges, glass plates with longitudinal grooves, cap-bars which span and cover the joints between said glass plates and have lower edges seated in longitudinal grooves in alinement with the supporting edges of said frame, the width of said grooves and the thickness of said lower edges being substantially the same, and securing devices, substantially as set forth.

40 2. A skylight structure comprising a metal frame having supporting edges, glass plates supported on said edges, rocking bearings comprising split tubes mounted on the supporting edges of the frame and between the plates and said supporting edges, and

means for holding the parts in place, substantially as set forth.

55

3. A skylight comprising sections connected together, each section comprising channel-irons, sections of corrugated glass supported on the upper edges of said channel-irons, cap bars covering the space between the adjacent edges of said glass sections and with one lower edge resting in a corrugation of said respective glass plates, and immediately over and in alinement with the supporting edges of said channel-iron, 60 tubular lead rocking bearings having longitudinal openings interposed between the supporting edges of said channel-iron and the glass plates, said longitudinal openings allowing of limited rocking movement 65 of the bearing tubes, clamping means for holding said parts in position, a support extending from beneath the upper end of one channel-iron to beneath the lower end of the adjacent channel-iron across the end of 70 said lower channel-iron, and means for securing said support, substantially as set forth.

4. A skylight structure comprising channel-irons having upturned supporting edges, 80 glass sections supported on the upturned edges of said channel-irons, bearings consisting of tubular members having longitudinal openings, lead parts mounted to rock on the upper edges of said channel-irons and forming rests for said glass sections, 85 said glass sections being formed with longitudinal grooves or corrugations in their upper surfaces, a cap bar having down-turned edges adapted to straddle the 90 space between the edges of said glass sections and having its lower edges fitted in said corrugations or grooves immediately over and in alinement with the supporting edges of said channel-irons, and means for 95 securing said parts together, substantially as set forth.

In witness whereof, I have hereunto set my hand and seal at Philadelphia, Pennsylvania, this 5th day of April, A. D. nineteen hundred and seventeen.

ARTHUR EDGECUMBE RENDLE. [L. S.]

Witnesses:

VINCENT P. MANFREDO,
ANTON KAUFMAN.
